UNITED STATES PATENT OFFICE.

THOMAS A. WHITE, OF KANSAS CITY, MISSOURI.

MOTOR.

1,186,353.

Specification of Letters Patent.

Patented June 6, 1916.

Application filed June 4, 1915. Serial No. 32,117.

To all whom it may concern:

Be it known that I, THOMAS A. WHITE, a citizen of the United States, residing at Kansas City, in the county of Jackson and 5 State of Missouri, have invented a new and useful Motor, of which the following is a specification.

This invention relates to a motor especially designed to be driven by air currents, 10 although it is to be understood that, with certain slight modifications, it can also be used as a water motor.

One of the objects of the invention is to provide means whereby the area of the 15 wings of the motor presented to the actuating current will be automatically reduced or increased, in proportion to the velocity of the actuating current, whereby the motor is maintained practically at a uniform speed 20 under the action of currents of varying velocities.

A further object is to provide a motor which can be readily and cheaply manufactured, has but few parts subjected to wear, 25 and which is of high efficiency.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without de- 35 parting from the spirit of the invention.

In the accompanying drawings the preferred form of the invention has been shown.

In said drawings:—Figure 1 is a perspective view of a motor embodying the 40 present improvements, certain of the parts being broken away and some of the parts being exaggerated to better illustrate the construction. Fig. 2 is a central vertical section through the base of the head of the 45 motor and the table on which it is mounted. Fig. 3 is an enlarged section through the connection between the governor and the power transmitting sleeve.

Referring to the figures by characters of 50 reference 1 designates a suitable supporting structure on which is arranged a base or table 2 which, in the present instance, has a central upstanding boss 3 in which is arranged a boss 4. This boss is surrounded by 55 a gear 5 bolted or otherwise secured to the bottom of the ring-like base 6 of the motor

head, the fastening means in the present instance being indicated at 7. This head is formed with a counterbore 8 extending thereinto from the bottom thereof and arranged in said counterbore are upper and lower rings 9 carrying spaced anti-friction balls 10 or any other suitable anti-friction elements. Extending between the rings 9 so as to engage the anti-friction devices 10 60 is a bearing ring 11 fitting snugly about the bushing 4 and fastened in any suitable manner, as by means of bolts 12, to the boss 3. By providing bolts 7 and 12 for holding the parts together, it will be seen that the structure can be readily assembled and taken apart. Furthermore the arrangement of parts described and shown provides an efficient anti-friction bearing for the head so 65 that it can rotate freely under the action of 70 the motive current.

The gear 5 is constantly in mesh with a small gear 13 secured to the upper end of a driven shaft 14 which is preferably journaled in the base or table 2.

Upstanding from the base 6 is a core 15 although it is to be understood that this core may be dispensed with if desired. Extending radially from the core and fixedly attached to it are frames 16. In the structure illustrated, four of these frames are used, the same being spaced 90 degrees, but it is to be understood that this number may be increased if desired. Each frame is provided, at a point between its ends, with an 80 upstanding dividing strip 17 and journaled in each dividing strip and in the outer end of the frame are shafts 18 the inner ends of which are provided with gears 19 which constantly mesh with a rack bar 20 slidably 85 mounted in the upper and lower portions of the frame 16. Secured to each shaft 18 is a sail 21 of a suitable strong fabric and which is adapted to be rolled upon the shaft when the rack bar 20 is moved upwardly and to 90 be unrolled from the shaft when the rack bar is moved downwardly. The depending portions of the sails lie close to a backing 22 preferably made up of crossed wires 95 stretched upon the frame 16.

The frames 16 may be connected at their upper ends in any suitable manner, as by means of a disk 23 and extending through this disk and also through the bushing 4 is a shaft 24 adapted to rotate freely within the disk 23 and bushing 4 and carrying, at its upper end, a vane 25. A block 26 is 100 105 110 115

secured to and rotates with the shaft 24 and has a cross bar 27 fixedly connected thereto and preferably formed with upturned ends 28. To these ends of the bar are pivotally connected the side arms 29 of a governing paddle 30 of any preferred construction designed to offer resistance to the flow of motive current. Extending from the paddle at points above the axis of movement thereof are arms 31 and these arms are connected by links 32 to oppositely extending fingers 33 carried by a collar 34. Said collar is mounted for rotation upon a sleeve 35 which is slidably mounted on shaft 24 but the collar 15 is held against sliding movement relative to the sleeve by working within an annular groove 36 formed in said sleeve.

Extending from sleeve 35 are arms 37 and each of these arms is slidably and pivotally engaged by one end portion of a lever 38 fulcrumed, as at 39, upon a bearing member upstanding from and fixedly connected to one of the frames 16. The other end of each lever 38 is pivotally and slidably connected 25 to the upper end of the adjacent rack bar 20.

It is to be understood that the weight of the rack bars 20 is such as to hold the levers 38 normally in position to support the sleeve 35 in its elevated position and the paddle 30 30 in its elevated position. The vane 25 is constantly disposed at right angles to the axis of movement of the paddle 30 relative to the cross bar 27 so that the face of the paddle is thus presented constantly to the motive current.

When the paddle is in its normal or raised position the sails 21 are unrolled so as to practically cover the backings 22. Obviously, therefore, any motive current acting 40 on the motor will cause those sails, which are at one side of a machine, to press against the backing 22 and thus cause the head of the motor to revolve, while the sails at the other side of the motor will be forced away 45 from their backings or will feather. Consequently a current will thus set up a constant rotation of the motor and should the velocity of the current increase, the increased pressure exerted upon the paddle 30 will 50 cause the paddle to swing downwardly and to thrust through arms 31 and links 32 against sleeve 35 with the result that levers 38 will be actuated to raise the rack bars 20 and cause the shafts 18 to partly or entirely 55 wind the sails, the amount of this winding being dependent upon the extent of movement of paddle 30 under the action of

the motive current. Thus it will be seen that the rotation of the motor will be maintained practically uniform under the action of currents of varying velocities. 60

What is claimed is:—

1. In a current motor, a revoluble structure including radial frames, an open backing carried by each frame, separate sails on each frame and adapted to be pressed against the adjacent backings when brought to the active side of the motor, each sail hanging freely and being capable of independent feathering when moved against the current, a vane revoluble about a vertical axis, a tiltable current operated member revoluble with the vane, and means actuated by said member for either furling or unfurling the sails. 70

2. In a current motor, a revoluble structure including radial portions, an open backing carried by each of said portions, sails on said radial portions and adapted to be pressed against the adjacent backings when brought into the current at the active side of the motor, said sails being suspended freely and being capable of independent feathering when brought against the current, a vane mounted for rotation, a tiltable pressure operated member revoluble with the vane, and means operated by said member during the tilting movement thereof for winding or unwinding the sails simultaneously. 80

3. A current motor including a shaft, a vane secured thereto, a governing paddle revoluble with and adapted to swing upwardly and downwardly relative to the shaft, a member slidable on the shaft and connected to and actuated by the paddle, a revoluble structure on the shaft and including radial frames, a sail carried by each frame, a shaft supporting each sail, a gear upon each shaft, rack bars meshing with the gears, levers carried by the frame and connected to the slideable member and rack bars, and open sail backings carried by the frames and constituting means for holding the sails in active positions when brought to one side of the motor and across the path of the motive current. 90

In testimony that I claim the foregoing as my own, I have hereto affixed my signature in the presence of two witnesses.

THOMAS A. WHITE.
